UNITED STATES PATENT OFFICE.

FREDERICK WILLIAM SCHWERDTFEGER, OF NEW YORK, N. Y.

AIRSHIP-LANDING STATION.

Application filed September 3, 1925. Serial No. 54,313.

The invention relates to an improved airship landing station in which a mooring tower operates on and around the roof of a circular-built hangar.

Among the objects of my invention are, first, to accomplish the process of landing and of anchoring an airship within the hangar as well as of releasing an airship from within the hangar into the air without turning the broadsides of the airship against the wind during any of the aforesaid processes; second, to turn all airships located within the hangar in either direction around the centre of the hangar in order to launch aircrafts in the direction of the prevailing wind; third, to provide a novel construction of a composite mooring tower; fourth, to provide novel means of landing airships in a more expeditious manner than has been accomplished heretofore; fifth, to provide novel means of launching airships expeditiously; and sixth, to land, berth and launch airships without the use and application of vast labor forces.

The objects and advantages of my invention will be better understood when the following itemized description is read and compared with the accompanying drawings, my invention being in the construction, the combination, the arrangement, and the cooperation of parts of this airship landing station.

In the drawings

Fig. 1 is a perspective view of a complete airship landing station, constructed in accordance with my invention, comprising a circular-built airship hangar with its rotating floor and a mooring tower, the latter operating on the roof of said hangar, a part of which roof is shown as broken away to illustrate the interior of said hangar,

Fig. 2 is a perspective view of the complete, composite mooring tower, the main motor-car, and one airship truck, the carrier of the mooring tower extending below the roof of the hangar and being ready to be connected with the carrier of the main motor-car,

Fig. 3 is a side view, partly in section, of the tower central part of the mooring tower, also showing the arrangement of rail tracks on the roof of the hangar,

Fig. 4 is a perspective view of the mooring tower, the left side-structure of the

mooring tower shown incomplete and a part of the wall casing of the mooring tower shown as broken away to give a view of the elevator within the mooring tower,

Fig. 5 is a perspective view of the carrier of the composite mooring tower and the carrier of the main motor-car, fragments of the two carriers shown as broken away,

Fig. 6 is a top view of the carrier of the mooring tower partly in section,

Fig. 7 is a perspective view of the weight, which weight is shown on the line 2—2 of Fig. 6,

Fig. 8 is a perspective view of the upper part of the rear of the carrier of the mooring tower,

Fig. 9 is a fragmentary view of the rear upper part of the carrier of the main motor-car,

Fig. 10 is a top view of the carrier of the main motor-car on the line 3—3 of Fig. 5,

Fig. 11 is a plan view of the top structure of the mooring tower illustrating a grab line device,

Fig. 12 is a side view of the part on the line 4—4 of Fig. 11, roller chain with hooks not shown,

Fig. 13 is an interior vertical view of a section on the line 4—4 of Fig. 11, as it appears after the removal of the upper covering,

Fig. 14 is a top view of a section of a roller chain with hooks,

Fig. 15 is a view of one hook, a hook-holding frame, and three rollers of an endless roller chain,

Fig. 16 is a cross sectional view of Fig. 11 on the line 5—5, the roller chain with hooks not shown,

Fig. 17 is partly a fragmentary bottom view and partly a cross sectional view of Fig. 11 on the line 6—6,

Fig. 18 is a plan view of the rotating floor of the hangar, the covering and the double rail tracks of the floor shown as broken away in three places to illustrate the supporting construction and the circular rail tracks,

Fig. 19 is a vertical sectional side view of one quarter part of the interior of the hangar,

Fig. 20 is a perspective view of a main motor-car, its upstanding carrier turned toward the rotating device operating around the pillar in the centre of the hangar. The

upper part of the pillar and the rear of the motor car are shown as broken away,

Fig. 21 is a side view of a part of the rotating device along the line 7-7 of Fig. 20.

As seen in Figs. 1 and 18 of drawings, a circular-shaped hangar 9, having a roof 22 and a partly rotatable floor 11, is provided with a series of lateral entrances 10, and each of the latter gives access to a like series 10 of tracks 8, placed on the outer side of and radially to the hangar 9.

The rotatable floor 11 and the floor-space surrounding same also have a like series of radially placed tracks, in order to give the 15 airship 75 access to, or departure from the hangar 9. The airship 75 can be placed on and secured to a suitable rolling equipment, provided for each of such radial tracks 8 located on the rotatable floor 11, consisting 20 of a train comprising a front motor car 13, two or more airship-receiving trucks 14, and a rear motor car 15, which rolling equipment can be shifted from one to another radial track 8 by means of the rotatable floor 11.

As shown in Figs. 1, 18 and 19, the rotatable floor 11 does not cover the entire floor area of the hangar 9, but leaves a stationary section between the outer rim of said rotatable floor and the side-wall of the hangar, thus 30 furnishing a movable platform surrounded by a stationary platform, which arrangement may be replaced by a stationary platform surrounded by a movable platform, or by a similar device. The advantage of a platform movable along another platform, in combination with an airship station and especially within an airship hangar serving commercial purposes, is obvious, as such arrangement saves time and 35 labor in loading and unloading an airship and in transferring a load from one section of an airship station to another section thereof.

The circular tracks located below the rotatable floor 11 (Fig. 18) serve either as a 40 guide for the latter or can be utilized without the rotatable floor 11 for turning airships, fastened to vehicles, laterally around the center of the hangar 9.

A centrally located pillar 12 of the hangar 50 is provided with an elevator device 18, see Fig. 20, and gives access from the hangar-floor 11 to the hangar-roof 22. A number of radiating gangways 23 on the roof 22 provides means for transportation of passengers, freight, etc., between the pillar 12 and the outer portion of the roof 22. The aforementioned pillar 12 has an upwardly projecting elevator compartment 21, which is 55 surmounted by a wind-vane 19 and also by an electric searchlight mechanism 20, both needed for obvious professional reasons.

A movable mooring tower 24, see Figs. 1, 2, 3, and 4, is placed upon a circular track 60 with rails 25, which track is situated near

the outer periphery of the circular hangar-roof 22. An additional inner wheel-track 27, concentric to the outer track 25, supports a rear strut-extension 26 of the mooring tower 24. Said mooring tower is also provided 70 with two lateral side strut-extensions 28, having wheels to run on the outer wheel-track 25, for the purpose of strengthening the rigidity of said movable tower.

A staircase 26^a and a gangway 26^b run 75 through the rear strut-extension 26 to the entrance of the elevator 24^a, which latter communicates with the roof 22 with the uppermost portion of the mooring tower 24.

The outer face of the tower 24 has attached thereto a vertical carrier-guide 41 of hollow, rectangular shape, which has a vertical slot 42, extending from a position above the upper platform 43 of the mooring tower to its lower extremity below the roof 22. 80

Each of the aforesaid main motor cars 13 is provided with an upwardly extending carrier-guide 49 of the same cross section and provided with a like vertical slot as the carrier-guide 41 of the mooring tower. This 90 carrier-guide 49 rests upon a platform extension 60 of the trucks 13 and is secured thereto by struts 61.

A coupling 59 or the like (slidable over the lower end of the dependent carrier-guide 41 and over the upper end of the upstanding carrier-guide 49, serves as a jointure between both and effects a continuous, slotted guide from the main motor cars 13 to the upper platform 43 of the tower 24. 95

A guide-weight 44 having anti-friction rollers 45 is shown in Figs. 5, 6, 7, and 10, and fits into the interior of the carrier-guides 41 and 49. This weight 44 has a projecting nose 46 which extends outwardly 100 through the slot 42. This nose is funnel-shaped in order to receive the outer projecting bow-knob of an airship and can be securely fastened thereto by means of ropes or chains 80, see Fig. 7.

An upper cable 50 is attached to the weight 44 at 52 and passes over roller 54 to a winch 56; a lower rope 51, attached to guide-weight 44 at 53, passes beneath the idlers 57 58 to a winch 59^a of motor car 13. 110

A bolt 62 passing through apertures 63 in the side walls of carrier-guide 49 and through hooks 64 of guide-weight 44 holds the latter at certain designated, vertical positions within the carrier-guide 49. 115

Projecting pins 66 on the lower carrier-guide 49 serve to maintain the upper end of an adjustable ladder 65, which rises from the platform 60 of car 13. This ladder arrangement provides access from motor car 125 13 to the upper portion of the carrier-guide 49 and a guide-weight 44 when located within the guide 49.

In Fig. 20 is shown a device for holding the bow of an airship in a vertically self 130

adjusting position. The center pillar 12 is stationary and at a proper height is surrounded by the rotatable device 16.

A series of outwardly projecting, vertical sliding bars 17^a are spaced in accordance with the series of radial tracks 8 located on the rotatable floor 11; each bar 17^a is provided with a sliding buckle 17.

The motor car 13 has on its carrier-guide 10 49 a projecting casing 67, which latter contains a movable weight 68 (Fig. 10), to which is fastened a turnbuckle 69 projecting through the slot 70, the latter having end stops 71.

15 A hook 72 forms a part of this turnbuckle 69 and is designed to be fastened to the sliding buckle 17 of the device 16, as soon as the car 13 has advanced to the center pillar 12.

20 The aforesaid weight 68 will counteract the buoyancy of a floating airship, and the hooks and turnbuckle devices, explained before, provide for a flexible connection in the event that the floor 11, with its contents of 25 trucks etc. thereon, is rotated around the center pillar 12.

In order to land an airship 75 and deposit the same into the hangar 9, a catchline 81, see Fig. 1, is thrown or shot off from the 30 bow-end of the ship, and is designed to be held by a catching device installed within each wing 29, which latter projects horizontally from a housing placed on the upper platform 43 of the mooring tower 24. These 35 laterally projecting blades or wings 29 are provided with a number of catching hooks 33, see Fig. 11, into one or the other of which the catchline 81 becomes entangled.

A transmission cable 39 operated by hand 40 or other motive power and provided with guard-plates 40, and passing over transmission wheel 38 rotates the cable wheel 37 and gear wheels 30 by means of the endless roller chain 33^a, to which a number of hooks 33 is 45 attached by roller link attachments 34^a. A series of guide rollers 36 and projecting flanges 35 on geared wheels 30 provide safety guards for the roller chain 33^a. A similar arrangement is provided for each of the wings 29.

50 As seen in Fig. 12 this catching device is placed within a frame composed of outer sides 31, 32, properly connected with each other, and furnishing the necessary bearings for the geared wheels 30. The catching blades or wings 29 can be made stationary to the aforesaid housing or detachable therefrom.

55 After the bowline 81 from the airship has been secured in the aforesaid manner, an operator on the platform 43 inserts that line into the apertures 47 and 48 of nose 46 of weight 44, and passes the same over the idler 55 and thence fastens it to a winch, suitably placed on the platform 43.

The mooring cable 82, attached to the catchline 81 by means of a slidable ring, glides downwardly from the airship 75 along said line 81. The sliding ring is detached after the mooring cable 82 has been fastened 70 to the winch to which the line 81 had been fastened previously, which winch, not shown in drawings, serves to haul down the fore-part of the airship 75.

In conjunction herewith a number of movable winches 78, placed on radial tracks 79 between adjoining radial tracks 8 outside the hanger 9, operates the cables 83 connected to appropriate links on the sides of airship 75. The winch 76 on rear motor car 80 15 is connected to the stern end of the airship also by means of cables 83.

The winches 56, 59^a, 76 and 78 cooperate in hauling down the airship and bring the bow-point of the latter into the nose 46 of 85 guide-weight 44 and after the aforesaid bow-point is locked thereto by the chains 80, the catchline 81 and the mooring cable 82 are released.

The airship, having been hauled down, is 90 placed into the adjustable nettings and air-cushions with which the cradles 73 of the trucks 14 are equipped. Additional attachment hooks 77 are provided on the cradles 73 and on front and rear cars 13 and 15 for hold-down cables or anchor-links of the airship 75.

All running rail tracks 8, 25, 27, and 79 are 95 made channel-shaped, with the web thereof placed vertically, with the truck-wheels and tower-wheels, respectively, placed between the two horizontal flanges. This rail-arrangement serves to resist an upward lift of all vehicles 13, 14, 15, and 78 and strengthens the position of the mooring tower 24, 100 105 respectively.

After disconnection of the composite carrier-guide and after the removal of the mooring tower from above the entrance the airship is advanced into the hangar 9, coupled to the anchoring device 16, as described above, and is now properly landed.

The launching process is analogous to the landing process, but in a reversed order. The departing airship within the hanger 9 is placed into connection with an outside track 8, which latter in its radial direction corresponds to the direction of the prevailing wind, bow-end-on. The rolling equipment of cars and trucks 13, 14, and 15 hauls the airship into the open, the cables 83 manipulated by the various winches will 110 guide the airship upwardly and, when disconnected therefrom, permits the airship to depart.

115 The entire manipulation of landing and launching is principally a mechanical one, accomplished with the aid of a comparatively small crew of attendants. Risks of breakage, usually caused by winds striking the 120 125 130

airship broadside-on, are eliminated by the system of using radial tracks suitably arranged and corresponding to the direction of the prevailing winds.

5. The time consumed in landing and launching airships is expeditious and concise.

In contrast to airship stations of present days, my station, in addition to the advantages described heretofore, will harbor a 10 large number of airships within a comparatively small area.

I do not limit myself to the precise details of construction herein set forth, as it is obvious that various modifications may be 15 made therein, without departing from the essential features of my invention, as defined in the appended claims.

I claim:—

1. A station for landing and launching 20 airships, comprising a circular hangar, a pillar centrally located within the hangar, a number of radial tracks placed on the hangar-floor and rotatable around said central pillar, a movable mooring tower situated on 25 a circular track placed on the periphery of the hangar-roof, an elevator device from the hangar-floor to the hangar-roof, another elevator device within said mooring tower, a series of gangways located on the roof and 30 communicating between said elevator devices, a system of outer tracks radial to the hangar, and means of lowering and berthing airships into vehicles movable along said radial tracks and of depositing airships into 35 the hangar, as described.

2. In combination with an airship and its hangar, a system of stationary tracks placed without the hangar and radiating from such hangar, a number of tracks radiating from 40 an interior point of the hangar and in communication with a like number of radial tracks rotatable round about said interior point, the latter radial tracks adapted to be joined with said tracks radiating from the 45 hangar, a mooring tower movable on the roof of the hangar, a composite carrier-guide connecting the mooring tower to an airship berth beneath the mooring tower, a search-light mechanism and a wind-vane surmounting this station, said wind-vane designed to 50 locate the proper entrance of an airship and the correct exit for an airship departing from the hangar.

3. In combination with an airship station, a mooring tower equipped with a dependent carrier-guide, another carrier-guide forming a part of a vehicle located beneath the former carrier-guide, both carrier-guides adapted to be coupled to each other and 55 forming, when combined, a composite carrier-guide, and when disconnected two separate carrier-guides for the bow- or stern-end of an airship while lowering and raising the latter.

4. In combination with the mooring tower

of an airship station, a carrier-guide for the bow- or stern-end of an airship while lowering and raising the latter, said carrier-guide dependent from said tower and adapted to be extended longitudinally, a guide-weight supported by and movable along said carrier-guide and adapted to receive the bow of an airship or to be connected to the stern-end of an airship, to lower and to raise an airship, and to counteract the buoyancy of 75 a floating airship.

5. In combination with the mooring tower of an airship station, one or a number of horizontal wings extending outwardly from said tower, each of said wings supporting a 80 grab-line-catching device comprising a number of grab-hooks extending outwardly from said wings, a number of guide-rollers and guide-flanges adapted to guide said grab-line-catching device, and means to operate 85 the latter.

6. In combination with the hangar of an airship station, an airship berth movable along a circular track placed around a rotatable airship anchorage centrally located 90 within said hangar, a vehicle equipped with an upwardly rising carrier-guide for the bow- or stern-end of an airship, a guide-weight supported by and movable along said 95 carrier-guide, means to connect an anchoring line of an airship to said weight, the latter adapted to lower and to raise an airship and to counteract the buoyancy of a floating airship, another weight movable along a stand rising upwardly from said vehicle and provided with a flexible, outwardly extending fastening device adapted to be coupled to said rotatable airship anchorage within the hangar.

7. In an airship station and in combination with each other, a circular-shaped hangar, a hangar-pillar provided with an elevating device to the hangar-roof, a number of gangways located on said roof and giving access to an elevating device within a 105 mooring tower movable on circular tracks placed on said roof, a plurality of rail-tracks, radially extending from the floor-center of the hangar, rotatable around said floor-center, and communicating with stationary rail-tracks radiating from said hangar, a number of communicating hangar-doors between the inner and the outer radial tracks, a train consisting of a motor car, 110 equipped with winches, and an airship receiving truck having a cradle padded with adjustable and removable nettings and air-cushions, a composite carrier-guide, composed of an upper, slotted carrier-guide dependent from said mooring tower and of a lower slotted carrier-guide upwardly rising from said motor car or truck, a slotted coupling for uniting the two separate carrier-guides, an adjustable anchoring device rotatable about a pillar centrally located within 115

120

125

130

the hangar, a grab-line-catching device in a wing extending outwardly from the mooring tower, a number of auxiliary winches movable on ground tracks placed outside of the **5** hangar, a system of hauling down cables leading from an airship to said various winches, a channel-rail arrangement adapted to hold wheels to the bottom rail, means to

transport the aforesaid train from the exterior to the interior of the hangar and vice **10** versa and also from one to another of the afore-mentioned radial tracks, and anti-friction devices, as herein set forth.

In witness whereof, I have hereunto subscribed my name.

FREDERICK WILLIAM SCHWERDTFEGER.
